DESIGN FOR A VEHICLE TOY

Richard W. Larkin, Bell, Calif.

Application November 13, 1945, Serial No. 123,689

Term of patent 3½ years

(Cl. D34—15)

To all whom it may concern:

Be it known that I, Richard W. Larkin, a citizen of the United States, residing at Bell, in the county of Los Angeles and State of California, have invented a new, original, and ornamental Design for a Vehicle Toy, of which the following is a specification, reference being had to the accompanying drawing, forming part thereof.

Fig. 1 is a perspective view of a vehicle toy, showing my new design.

Fig. 2 is a top plan view of same.

I claim:

The ornamental design for a vehicle toy, substantially as shown.

RICHARD W. LARKIN.
